UNITED STATES PATENT OFFICE.

LOUIS H. ENSTEN, OF CLEVELAND, OHIO.

DESIGN FOR A CAP.

59,464.

Specification for Design.

Patented Oct. 25, 1921.

Application filed October 21, 1920. Serial No. 418,627. Term of patent 14 years.

To all whom it may concern:

Be it known that I, LOUIS H. ENSTEN, a citizen of the United States, residing at Cleveland, in the county of Cuyahoga and State of Ohio, have invented a new, original, and ornamental Design for Caps, of which the following is a specification, reference being had to the accompanying drawing, forming a part hereof, and in which—

Figure 1 is a perspective view of the cap constructed in accordance with my design; Fig. 2 is a front view of the same and Fig. 3 a rear view.

I claim:—

The ornamental design for a cap as shown.

LOUIS H. ENSTEN.
